UNITED STATES PATENT OFFICE.

EDWARD M. HARBERTON, OF LOS ANGELES, CALIFORNIA.

BASE-BALL MACHINE.

1,144,472.

Specification of Letters Patent. Patented June 29, 1915.

Application filed March 11, 1915. Serial No. 13,780.

To all whom it may concern:

Be it known that I, EDWARD M. HARBERTON, a citizen of the United States, residing at Los Angeles, in the county of Los Angeles and State of California, have invented a new and useful Base-Ball Machine, of which the following is a specification.

My object is to make a machine for playing base ball, or the like, in which the game will be entirely mechanical with the exception of the operator and the batter; and my invention consists of the novel features herein shown, described and claimed.

Figure 1 is a diagrammatic perspective illustrating my base ball machine. Fig. 2 is a fragmentary sectional detail on the line 2—2 of Fig. 1 upon an enlarged scale. Fig. 3 is a fragmentary sectional detail on the line 3—3 of Fig. 2. Fig. 4 is a diagrammatic perspective upon an enlarged scale, the mechanical field being omitted. Fig. 5 is an enlarged fragmentary sectional detail of the base ball gun. Fig. 6 is a vertical sectional detail upon an enlarged scale upon the line 6—6 of Fig. 7. Fig. 7 is a horizontal sectional detail on the line 7—7 of Figs. 4 and 6. Fig. 8 is an enlarged fragmentary plan of the discharge end of the gun barrel and showing the curver in position for use, as indicated by the arrow 8 in Fig. 5. Fig. 9 is a cross sectional detail on the line 9—9 of Figs. 5 and 8. Fig. 10 is a fragmentary plan of the sliding cross-head and clutch mechanism for operating the gun, as indicated by the arrow 10 in Fig. 4. Fig. 11 is a vertical sectional detail on the line 11—11 of Fig. 10.

A base ball machine embodying the principles of my invention comprises a ball gun 1, the mechanical ball field 2, the imitation pitcher 3, the controller 4 connected to the gun 1, and the machine thus constructed is intended to be operated in a room or hall, like a shooting gallery, which is entirely inclosed, the front end of the room being a coarse screen 5.

The details of the base ball gun 1 are as follows: The gun barrel 6 has a bore 7 large enough to carry the base ball 8; the barrel 6 is fixed through the center of the piston casing head 9, a piston casing 10 is fixed to the head 9 and the piston head 11 fits in the casing 10. Spring casings 12 are fixed through the head 9 around the barrel 6 and the retractile coil springs 13 are mounted in the spring casings 12. Caps 14 are

mounted upon the forward ends of the casings 12, screw eyes 15 extend through the caps 14 and connect to the forward ends of the springs 13, there being nuts 16 upon the screws against the caps for adjusting the tension upon the springs. The rear ends of the springs 13 are connected to eye-bolts 17 fixed in the piston head 11. The tension of the springs 13 is exerted to pull the piston head 11 toward the piston casing head 9. The feed pipe 18 discharges into the gun barrel 6 near its rear end. A rigid cross-head 19 is fixed diametrically across the rear end of the piston casing 10 and the piston rod 20 is fixed to the piston head 11 and slides through the bearing in the center of the cross-head 19 and extending backwardly through the guide bearing 21 fixed in the frame 22. An expansive coil spring 23 is mounted around the piston rod 20 between the cross bar 19 and the piston head 11, the tension of said springs serving to add to the power of the piston in coöperation with the springs 13. Guide bars 24 and 25 extend from the ends of the rigid cross-head 19 backwardly to the ends of the guide bearing 21 parallel with the piston rod 20. The sliding cross-head 26 is mounted upon the piston rod 20 and secured thereto by the pin 27, and said cross-head is slidingly mounted upon the bars 24 and 25. A clevis 28 extends backwardly from the sliding cross-head 26. The bearing block 29 is slidingly mounted upon the piston rod 20 and a hook 30 is pivotally connected to the bearing block 29 and adapted to hook into the clevis 28, there being a guide finger 31 upon the hook, so that as the bearing block 29 approaches the clevis, the guide finger 31 will slide over the clutch bar 32 of the clevis. An ear 33 extends upwardly from the hook 30 and a cord 34 is attached to the ear, so that by pulling the cord 34 the hook may be released from the clevis and the piston allowed to snap or shoot. The cord 34 extends over the guide pulley 35 under the guide pulley 36 to and under the guide pulley 37 to the end ring 38, so that the operator 39 may release and fire the gun by pulling the ring 38. A lever 40 is pivotally mounted upon the shaft 41 fixed in the frame 22, the upper end of the lever being bifurcated to spread the fingers 42 and 43 so as to straddle the piston rod 20 and links 44 connect the fingers 42 and 43 to the bearing block 29. A cord 45 connects the lower end

of the lever 40 to the sliding rack 46, said rack 46 being mounted upon the base 47. A hand lever 48 is mounted to vibrate lengthwise of the rack 46 and the pawl 49 carried by the hand lever engages the teeth of the rack so as to move the rack 46 away from the gun. A retaining pawl 50 holds the rack from going backwardly, so that as the hand lever 48 is operated, the rack 46 will move 5 upwardly step by step and pull upon the cord 45, thereby moving the lever 40 to pull the piston head 11 backwardly against the tension of the springs. A cord 51 connects the lower end of the lever 40 around the 10 guide pulley 52 to and around the guide pulley 53 to the ring 54, said ring 54 being in position near the operator 39, so that, when he desires, the operator may pull the ring 54 and return the hook 30 to the clevis. 15 A slide valve casing 55 is incorporated into the feed pipe 18 and the slide valve 56 is mounted in this casing, said slide valve having a vertical opening 57, registering with the opening 58 in the feed pipe, so as to 20 allow the balls to pass downwardly through the feed pipe into the gun barrel. An arm 59 extends upwardly from the block forming the valve 56 and has fingers 60 extending into the slot 61 in the feed pipe 18, so 25 that when the valve 56 is pulled backwardly, the lower one of the balls 62 will rest upon the imperforate part of the valve 56 and then, when the valve slides forwardly, the fingers 60 will pass into the slot 61 above 30 the lower ball 62 and hold the upper ball 63, while the lower ball 62 falls through the opening 57 into the gun. A cord 64 is connected to the valve 56 and extends around the guide pulley 65 and is connected to the 35 upper end of the finger 42 of the lever 40. A second cord 66 is connected to the post 59 and extends around a guide pulley 67 fixed upon the casing 55 and is connected to the upper end of the finger 42 of the lever 40, 40 so that the feed valve is operated in proper relation to the gun, that is—suppose that the lever 48 is operated to move the rack 46 forwardly to pull the piston head 11 backwardly, the line of transmission being 45 50 through the cord 45 to the lever 40 through the links 44 to the cross-head 26 and then through the piston rod and also through the fingers 42 and through the cords 66 to the valve 56, so that as the piston head 11 is 55 pulled backwardly, the valve 56 is moved forwardly to discharge the ball into the gun. Then, when the operator pulls the ring 38, the gun is discharged shooting the ball 18 out of the barrel 6. Then, when the operator 60 65 pulls the ring 54, the line of transmission through the cord 51 moves the lever 40 to connect the hook 30 to the piston mechanism and at the same time pulls the cord 64 to move the valve 56 backwardly to release the ball 63 down upon the imperforate

part of the valve 56 ready to be discharged into the gun at the next operation. The supply of balls is thrown into the hopper having a bottom 68 and a pipe 69 leading into the feed pipe 18.

The curver 70 is mounted upon the forward end of the gun barrel 6. The details of the curver 7 are as follows: A channel iron ring 71 is fixed upon the end of the gun barrel 6 and a second ring 72 is loosely mounted in the channel of this first ring. An arm 73 is connected to the ring 72 by a pivot pin 74, said arm being normally parallel with the gun barrel 6. Fingers 75 and 76 are connected together and pivotally connected to the forward end of the arm 73 by the pivot pin 77 and a bar 78 extends backwardly from the fingers 75 and 76 past the pin 77 and a bolt 79 is inserted through the bar 78 through the arm 73 and 80 through the expansive coiled spring 80 and an adjusting nut 81 is fixed upon the bolt 79, for adjusting the tension upon the fingers 75 and 76. The fingers 75 and 76 extend forwardly from the gun barrel 6 85 and swing in and out toward the line of the bore 7, so that as the ball passes from the bore 7 it will contact with the fingers and the curvature thus imparted to the ball may be regulated by the tension of the 90 fingers adjusted by the nut 81. A cord 82 connects the rear end of the arm 73 to the lug 83 fixed upon the ring 72 to form a stop and limit the swing of the arm 73 in one direction. A spring 84 connects the rear 95 end of the arm 73 to the lug 85 fixed to the ring 72 and upon the opposite side from the lug 83, the tension of the spring 84 being exerted to hold the arm 73 in its straight parallel position. The stop 86 is fixed in 100 the gun barrel 6, so that when the ring 72 is moved to bring the rear end of the arm 73 against the stop 86, further movement of the spring 84 will cause the forward end of the arm 73 to swing laterally, so as to 105 bring the fingers 75 and 76 out of the path of the balls, as when it is desired to shoot a straight ball. A cord 87 is attached to the link 88 and extends downwardly around the guide pulley 89 and forwardly around 110 the winding drum 90 several times and then backwardly under the guide pulley 91 and upwardly on the opposite side of the gun barrel to the opposite end of the link 88 and the winding drum 91 is operated by 115 the hand lever 92, so that when the hand lever is moved forwardly, as indicated by the arrow 93, the ring 72 is moved in the direction indicated by the arrow 94 in Fig. 9, that is—toward the stop 86, and when 120 the hand lever is moved backwardly in the direction indicated by the arrow 95, the ring 72 is moved in the direction indicated by the arrow 96, or away from the stop 86. In this way, the fingers 75 and 76 may move 125

entirely around the track of the ball, as required to curve the ball to the right, or to the left, or up or down, or in any desired direction, or they may be moved entirely out 5 of operation, as required to shoot a straight ball.

The details of the mechanical base ball field 2 are as follows: Side boards 97 and 98 are connected by the front wall 99 and

10 the rear wall 100. The gun barrel 6 extends through the center of the upper part of the wall 99. The upper edges of the walls 97 and 98 are stepped and the wall 101 forms the front face of the second step, 15 the wall 102 the front face of the third step, and the wall 103 the front face of the fourth step. A shaft 105 extends from the wall 97 to the wall 98 in front of the wall 101 at the first step; a shaft 106 is similarly mounted 20 for the second step; a shaft 107 for the third step and a shaft 108 for the fourth step. Posts 109 are pivotally mounted upon the shafts 105, 106, 107 and 108 and the bases 110 are fixed upon the upper ends of

25 these posts. The bases 110 are flat round plates marked 1st base, 2nd base, 3rd base, etc., and stop bars 111 are mounted behind the lower ends of the posts, when in their upright positions, so that the posts will 30 overbalance slightly forwardly and remain in their upright positions until the indicators 112 are fixed upon the lower ends of the posts, so that when a base is hit, the post will fall over backward against the stops 35 113 and the indicators 112 will come into view, so that the score-keeper may take the score from the bases that have been hit. The stops 113 are connected to the shafts 105, 106, 107 and 108 by arms 115 and cords

40 116 are connected to the stops 113, so that by pulling the cords, the bases may be uprighted. The balls which pass over the wall 101 will fall downwardly upon the floor 68 and all parts of the floor 68 are inclined to 45 ward the pipe 69, so that the balls will return to the feed valve. Any other balls must be picked up and thrown into the hopper.

The details of the imitation pitcher 3 are as follows: The image 117 stands in 50 front of the gun 1 and the arm of the image has a spring shoulder 118 and a spring elbow 119. A cord 120 connects to the forearm 121 and extends upwardly in front of the spring elbow through a bearing in the upper part 122 of the arm and then backwardly and is connected to the bracket 123 extending downwardly from the cross-head

26, so that when the controller 4 is operated to pull back the piston and shoot a ball, the arm will be thrown into a pitching position 60 as shown in Fig. 1. A ball 124 is carried in the hand of the image, the object being to give the best possible mechanical imitation of a pitcher.

The details of the controller 4 have al- 65 ready been described.

The batter 125 stands behind the screen wall 5 and the operator is in front of the wall. The wall 5 is made in two sections overlapping and some distance apart, so 70 as to make a passage-way 126, making a zigzag passage through the wall, which is not likely to be penetrated by balls coming from the gun, and the wall is open screen work so that the entire mechanism is in 75 full view of the operator.

The details of construction may be varied in many ways without departing from the spirit of my invention, as set up in the following claims.

80

I claim:

1. A base ball machine, comprising an air gun, means for feeding the balls one at a time into the air gun, an imitation pitcher mounted to be operated in unison with the 85 air gun, means for charging the gun, and means for firing the gun.

2. A base ball machine, comprising an imitation base ball field, mechanism adapted for throwing the balls, and an imitation 90 pitcher operated in unison with the ball-throwing mechanism.

3. In a base ball machine, an air gun, a curver mounted upon the muzzle of the air gun, an imitation pitcher mounted in 95 front of the air gun to be operated in unison therewith, means for charging the gun and means for firing the gun.

4. In a base ball machine, an air gun, an imitation pitcher mounted to be operated 100 in unison with the air gun, and a controller mechanism for charging and firing the gun.

5. In a base ball machine, an imitation field, indicators mounted in the imitation field to mark first base, second base, and 105 third base, an air gun discharging from the imitation field, an imitation pitcher mounted to be operated in unison with the air gun, and controller mechanism for charging and firing the gun.

EDWARD M. HARBERTSON.
